UNITED STATES PATENT OFFICE.

WILLIAM P. BETTENDORF, OF DAVENPORT, IOWA; J. W. BETTENDORF ADMINISTRATOR
OF SAID WILLIAM P. BETTENDORF, DECEASED.

UNDERFRAME FOR CARS.

1,234,269.

Specification of Letters Patent. Patented July 24, 1917.

Application filed March 13, 1907. Serial No. 362,176.

To all whom it may concern:

Be it known that I, WILLIAM P. BETTENDORF, a citizen of the United States, and a resident of Davenport, in the county of Scott and State of Iowa, have invented certain new and useful Improvements in Underframes for Cars, of which the following is a clear, full, and exact description.

My invention relates to metallic underframes for cars, and its object is to so construct the same that a single center-sill can be used between the body-bolster, and yet receive the thrust and strain imparted to the same through parallel center-sills interposed between the body-bolsters and the end-sills of the car, and a further object is to materially reduce the weight of the underframe, and to simplify the construction, so that the greatest strength consistent with the simplest structure will be secured, and so that the needle-bars connecting the side-frames can be continuous from side to side of the car and so disposed that the floor of the car can be secured to the floor timbers, suitably supported by and attached to the same, so that the flooring will rest upon the upper flanges of the center and side sills, substantially as hereinafter fully described and as particularly pointed out in the claims.

In the drawings:—

Figure 1 is a plan view of my invention.

Fig. 2 is a central longitudinal section of the same, drawn to a slightly larger scale.

Fig. 3 is a transverse section taken on dotted line 3—3, Fig. 1, looking in the direction indicated by the arrows.

Fig. 4 is a transverse section taken on dotted line 4—4, Fig. 1, looking in the direction indicated by the arrows.

Fig. 5 is a transverse section of a portion of the underframe, taken on dotted line 5—5, Fig. 2.

Fig. 6 is a horizontal longitudinal section of the bifurcated end portion of said center-sills.

Fig. 7 is a perspective view of the parallel members of the bifurcated end portion of said sill together with the adjacent end of the intermediate single portion thereof in position for properly assembling the same.

Referring to the drawings A represents the side-sills of my invention; B the end-sills, and C the body-bolster thereof. The end-sills may be of any desired construction, although I prefer to make them of pressed

steel, and the side-sills are made of Z-bars, which are connected at their ends to the end-sills in any suitable manner and are connected together at suitable points between the body-bolsters, by a series of transverse 60 needle-bars, D. These needle-bars D are, preferably, made of I-beams, and they are secured to said side-sills, both by rivets extending through their own upper flanges and the lower outwardly projecting flanges 65 of said side-sills, and by blocks a connected by rivets to the inner surfaces of the vertical webs of said side-sills, and in like manner to their upper flanges.

The body-bolsters C, preferably consist of 70 parallel I-beams, which are connected to the side-sills in substantially the same manner as the needle-beams, and the I-beams composing these body-bolsters are connected at their centers of length by a suitable separator and underneath, by the usual female bearing-plate k, and are also connected between their centers of length and their ends by suitable side-bearings. I make no particular claim herein to the construction of 75 the body-bolster and the only feature in connection with it, and to which attention is called, is that the I-beams used in its construction are about the same in dimensions as the needle-beams D, and are in the same 85 horizontal plane.

Between the end-sills and the bolsters of my improved underframe the center-sill comprises a single rolled metal beam, E, preferably, of an I-beam shape and of such 90 dimensions that the central portion of its body is of a height extending from the floor of the car to about the horizontal plane intersecting the axes of the car-wheels. This central portion, E, is provided with suitable 95 transverse openings to permit of the passage of the needle-beams therethrough, and these openings are reinforced by plates b on one or both sides of the vertical web of the I-beam, which plates are, preferably, provided with flanges projecting horizontally from them, that lap against and embrace both the upper and lower flanges of the needle-beam in the vicinity of said openings. The ends of this I-beam portion of the center-sill are reduced in height, in any suitable manner, so as to incline their lower flanges upward until they are in the same horizontal plane as the lower flanges of the I-beam bolsters and needle-beams, and so as to give 100 105 110

them a truss-shape, and the vertical web at each end thereof is embraced between and secured to the rearwardly extending plates *e* of the converging rear ends of the members *F* of the cast metal bifurcated ends of said center-sill. These parallel members *F* practically form bifurcated extensions of the ends of the single I-beam constituting the central portion of the center-sill, and they 10 extend over the body-bolsters to the end-sills, between which latter and said body-bolsters said members are constructed so as to operatively support and retain the draft-rigging between them. The ends of the 15 members *F*, *F*, farthest from the end-sills converge toward each other, and on the side of the body-bolster farthest from the members the upper flanges *d*', *d*', of the parallel end-sills are stepped downward and their 20 lower flanges are stepped upward to form shoulders *d*, against which the ends of the flanges of the single center-sill are seated and receive the end-thrust of the parallel members *F* transmitted to them through the 25 draft rigging. Immediately in front of the ends of the single I-beam portion of the center-sill the parallel end-members, *F*, are cut away or recessed upward from their lower edges to arch over the body-bolster, and the 30 upper edges of the arches so made are provided with horizontal flanges *e*, projecting from the inner opposing surfaces of said parallel sills to such an extent, that their edges meet, substantially as shown in Fig. 6 35 of the drawings. The meeting edges of these flanges *e*, *e*, are suitably recessed to form a king-bolt bearing *e*', and the rear ends thereof terminate in vertical walls *f* of such dimensions that they extend through 40 the archway beyond the outer side of said members *F*, and form, together with a similar vertical wall *g* on the opposite side of the archway, (which extends through this archway and terminates in a bracket separating the forward ends of the flange *e* and a horizontal flange *h* projecting from the outer surfaces of said sills *F* in the same plane as flanges *e*), a passage-way for the body-bolsters, substantially as shown in the 45 drawings. The forward ends of the said parallel end members *F* extend through a suitable opening in the end-sill *B* of the underframe and are suitably secured thereto and have their upper inwardly projecting 50 flanges *d* converge inward toward each other until they meet. If desired, the female bearing-plate *k*, of the bolster can not only be riveted to the under flanges of the I-beams composing the body-bolsters, but its 55 edges can extend sufficiently to enable them to be riveted to the flanges of the ends of the single I-beam central portion of the center-sill and to the lower flanges of the portion of the parallel end members on the 60 opposite side of the body-bolster connecting 65

the lower edges of the wall *g* of the bolster passageway and the vertical web of said parallel members. I also rivet the flanges *e* and *h* to the upper flanges of the I-beams of the body-bolster. This is done, however, 70 not for the purpose of transmitting the shock or strain transmitted to the center-sill by the draft-rigging, but more for the purpose of assembling said parts in their proper relative positions. Thus construct- 75 ed the hauling shock and strain to which the car is subjected is transmitted from end to end of the car through the parallel end members of the center-sill and the single I-beam central portion of the same, and does 80 not materially subject the body-bolsters to the lateral thrust of the center-sill where the lines of draft intersect the same.

The floor-beams *K* of the car are fastened in a suitable manner directly to the upper flanges of the bolsters and needle-beams, and the flooring *J* while resting upon the upper flanges, the side-sills and center-sills, is secured to the floor-beams in a much easier and convenient way than could be done if 85 secured directly to said center and side-sills.

It will be observed that an important advantage in extending the parallel draft members *F* through an opening in the end sill *B* is that all the bumping strains are 90 taken up by the draft members, thereby relieving the end sill of such strains and thus permitting it and the superstructure of the car to be made of minimum weight of metal. 95 It is preferred that these projecting ends of the draft sills *F* shall be connected by a striking or bumping plate *n*, as shown in Fig. 2, the front ends of the draft members 100 being provided with holes *o* to receive the 105 bolts which fasten this plate to the draft members.

Between the extended ends of the draft sills *F*, at the lower front corners thereof, I mount a horizontal bar *p*, this bar being 110 secured between the draft sills by a horizontal bolt *q* extending entirely through the bar *p* and through holes *r* formed in the draft sills. This bar acts as a support for the shank of the coupler, and by reason of the fact that this securing bolt is arranged horizontally, it will be seen that the liability 115 of the bolt working loose and thus dropping the coupler is reduced to a minimum. It will also be seen that with this arrangement 120 it will be a very simple matter to renew the carrier bar *p* when worn or broken.

What I claim as new is:—

1. An underframe for cars comprising end-sills, body-bolsters, a single center-sill 125 disposed between said body-bolsters, and draft-sills the rear ends of which extend past said body-bolsters and bend toward and lap past the adjacent end of the center-sill.
2. An underframe for cars comprising 130

side-sills, end-sills, body-bolsters, a single center-sill disposed between said body-bolsters, and draft-sills the front ends of which are connected to the end-sills and the rear ends of which extend over said bolsters and bend toward and lap past the adjacent end of center-sills.

3. An underframe for cars comprising a center-sill the ends of which extending from the end-sills over the body-bolsters consist of two parallel cast metal members, and the central portion of which between said bolsters consists of a single rolled metal beam.

4. An underframe for cars comprising a center-sill the central portion of which consists of a single longitudinal rolled metal beam and the ends of which consist of two parallel cast metal members which extend over the body-bolster and are provided with extension-plates between which the ends of said central beam portion are suitably secured.

5. An underframe for cars comprising a center-sill, the central portion of which consists of a single longitudinal rolled metal beam and the ends of which consist of two parallel cast metal members which extend over the body-bolsters and converge toward each other, and plates extending from their inner converging ends between which the ends of said rolled beam central portion are suitably secured.

6. An underframe for cars comprising a center-sill, the central portion of which consists of a longitudinally disposed rolled metal beam, and the ends of which consist of two parallel cast metal members having plates extending from their ends and shoulders at the roots of said plates against which the ends of said central beam portion abut when placed and secured between said plates.

7. An underframe for cars comprising a center-sill, the central portion of which consists of a longitudinally disposed rolled metal beam, and the ends of which consist of two parallel cast metal members having plates extending from their ends and shoulders at the roots of said plates made by stepping the upper and lower edges thereof against which the ends of said central beam portion abut when placed and secured between said plates.

8. An underframe for cars comprising a center-sill, the central portion of which consists of a longitudinally disposed rolled metal beam, and the ends of which consist of two parallel cast metal members extending over the body-bolster and having plates extending from their ends and shoulders at the roots of said plates against which the ends of said central beam portion abut when placed and secured between said plates.

9. An underframe for cars comprising a center-sill, the central portion of which con-

sists of a longitudinally disposed rolled metal beam, and the ends of which consist of two parallel cast metal members extending over the body-bolster and having plates extending from their ends and shoulders at the roots of said plates made by stepping the upper and lower edges thereof against which the ends of said central beam portion abut when placed and secured between said plates.

10. An underframe for cars comprising a center-sill, the central portion of which consists of a longitudinally disposed rolled metal beam, and the ends of which consist of two parallel cast metal members, the ends of which adjacent to the body-bolster converge toward each other and have plates extending from their ends and shoulders at the roots of said plates against which the ends of said central beam portion abut when placed and secured between said plates.

11. An underframe for cars comprising a center-sill, the central portion of which consists of a longitudinally disposed rolled metal beam, and the ends of which consist of two parallel cast metal members the ends of which adjacent to the body-bolster converge toward each other and have plates extending from their ends and shoulders at the roots of said plates made by stepping the upper and lower edges thereof against which the ends of said central beam portion abut when placed and secured between said plates.

12. An underframe for cars comprising a center-sill, the central portion of which consists of a longitudinally disposed rolled metal beam, and the ends of which consist of two parallel cast metal members, the ends of which adjacent to the body-bolster converge toward each other, and extend over the body-bolster and have plates extending from their ends and shoulders at the roots of said plates against which the ends of said central beam portion abut when placed and secured between said plates.

13. An underframe for cars comprising a center-sill, the central portion of which consists of a longitudinally disposed rolled metal beam, and the ends of which consist of two parallel cast metal members the ends of which adjacent to the body-bolster converge toward each other and extend over the body-bolster and have plates extending from their ends and shoulders at the roots of said plates made by stepping the upper and lower edges thereof against which the ends of said central beam portion abut when placed and secured between said plates.

14. An underframe for cars comprising a center-sill, the central portion of which consists of a single longitudinal rolled metal beam and the ends of which consist of two parallel cast metal members the lower edges of the end portion farthest from the end-

- sills of which are recessed to permit of the passage therethrough of the body bolster and are directly connected to said central beam portion.
- 5 15. An underframe for cars comprising a center-sill, the central portion of which consists of a single longitudinally disposed rolled metal beam and the ends of which consist of two parallel cast metal members the lower edges of the end portion of which farthest from the end-sills are recessed and provided with transverse flanges to form a passageway for the body-bolsters, and which are connected directly to said central rolled metal beam portion.
- 10 16. An underframe for cars comprising a center-sill, the central portion of which consists of a single longitudinally disposed rolled metal beam, and the ends of which consist of two parallel cast metal members having integral plates extending from their ends between which the ends of said central rolled beam portion are suitably secured, and the under edges of which adjacent thereto are provided with recesses, the edges of which are flanged transversely to provide a passageway for the body-bolster.
- 15 17. In car construction, in combination, body-bolsters, a single integral center-sill of substantially I-cross-section disposed between and terminating adjacent to said bolsters, a pair of relatively spaced draft-sills having their rear ends lap past and closely embrace and rest substantially against opposite sides of the web of the adjacent ends of said center-sill and secured thereto, and side-sills, said side-sills and center-sill being so positioned as to carry directly the flooring and floor timbers of the car.
- 20 18. In car construction, in combination, a pair of side sills, a bolster consisting of I-beams stretched between said side sills, a single integral center sill of substantially I-cross-section terminating adjacent said bolster, and a pair of relatively spaced draft sills having their inner ends closely embracing and resting substantially against opposite sides of the web of said center sill and secured thereto.
- 25 19. In car construction, in combination, a pair of side sills, a bolster consisting of I-beams stretched between said side sills, a single integral center sill of substantially I-cross-section terminating adjacent said bolster, and a pair of relatively spaced draft sills having their inner end portions embracing and rigidly connected with opposite sides of the web of said center sill and secured thereto, said side sills, bolster and center sill being so positioned as to carry directly the flooring and floor timbers of the car.
- 30 20. In car construction, in combination, a pair of side sills, a bolster consisting of I-beams stretched between said side sills, a single integral center sill of substantially I-cross-section terminating adjacent said bolster, and a pair of relatively spaced draft sills having their rear end portions lap past and embrace and rigidly connected with opposite sides of the adjacent ends of the web of said center sill and secured thereto.
- 35 In testimony whereof I have hereunto set my hand and seal this 9th day of March, 1907.
